UNITED STATES PATENT OFFICE.

JACOB B. WALLACE, OF ERIE, PENNSYLVANIA.

GAS-BURNER FOR STOVES.

SPECIFICATION forming part of Letters Patent No. 527,566, dated October 16, 1894.

Application filed December 14, 1893. Serial No. 493,668. (No model.)

To all whom it may concern:

Be it known that I, JACOB B. WALLACE, a citizen of the United States, residing at Erie, in the county of Erie and State of Pennsylvania, have invented certain new and useful Improvements in Gas-Burners for Stoves; and I do hereby declare the following to be a full, clear, and exact description of the invention, such as will enable others skilled in the art to 10 which it appertains to make and use the same.

This invention relates to gas burners for stoves, and consists in certain improvements in the construction thereof as will be herein-after fully described and pointed out in the 15 claims.

The invention is illustrated in the accompanying drawings as follows:

Figure 1 shows a plan of a burner and its connections made in accordance with my invention, the top of the stove being removed and the mixer and contiguous parts in section. Fig. 2 is a section of said burner on the lines 2—2—2—2.

A marks the main burner; A', a simmering burner placed within the main burner; B, the feed pipe of the main burner; B', the feed pipe of the simmering burner; C, the mixer; c, the jet orifice; D, the controlling cock; E, the gas supply pipe; F, the stove top; and F' 30 the side of the stove.

The bodies of the burners, a, may be made of any desired contour. A burner cap, a', with its sides preferably at an angle, as shown, is placed on the burner body and has 35 the burner jets, a², passing through the cap perpendicularly to it, thereby giving them an upward and outward tendency.

Extending upwardly from the burner cap, a', are studs, a³, about an eighth of an inch 40 in height, and on these studs rest the roof caps, A² the roof cap of the main burner being ring shaped, allowing the jets to pass both inwardly and outwardly around it from the inwardly and outwardly directed jet orifices of the main burner.

Screws, a⁴, are passed through the roof cap, studs and burner cap, and are screwed into the bottom of the burner body, thus holding the parts tightly together. The roof cap is 45 of sufficient width to project over the burner jets. This keeps the jets clear of the usual accumulations on the burners caused among

other things by the frequent overflow of vessels heated by them, and insures a clean and even flow from each jet. In order that the 55 roof cap may be effective for this purpose it is necessary that the under side should be substantially flat or inclined from the edges, as otherwise (where there is a declination from the edges) the adhesive quality of the liquids 60 which this roof cap is intended to shed will carry said liquids along the under surface of said cap and over and onto the burner.

The direction of the jets is such that the flame strikes the lower edges of the roof caps, 65 and this gives it the proper lateral deflection. By placing the ring shaped roof cap over the main burner on studs, a³, an air space is made between the burner and the roof cap. This gives a free circulation of air on all sides of 70 the jets, and insures a sufficient air exposure to obtain perfect combustion, and it also forms a communicating passage between the outer and inner jets so that either will light from the other, without any appreciable explosion, as there would be, if they were allowed to light, one from the other, over the top of the cap. These burners are intended to be used separately; the main burner when it is desired to have a large fire, and the simmering burner when, as its name implies, it is desired to have a very small one. Burners have hitherto been so arranged, but with a 75 separate mixer and its connections for each burner.

In my device, the burners are pivoted to the stove preferably at the side opposite that from which the feed pipes lead, and as far from the burner as is possible in the limited space of the stove, so the arc of movement of 80 the mixer ends of the feed pipes may be as near a straight line as possible. In the construction shown in the drawings an arm, G, is attached to the burners, and is hinged or pivoted to the stove top at, g. The feed pipe 85 of the simmering burner passes under the main burner, and the mixer ends of the pipes rest on the shoulder, f, on the stove side, and a handle, H, extends from them through the slot, f', in the stove side. By pushing the 90 handle from right to left or vice versa either feed pipe may be swung before the single jet orifice, c. By this construction it is possible to supply any one of two or more burners 95 100

from one mixer and jet orifice, and the change can be accomplished by means of the handle from without the stove frame.

What I claim as new is—

- 5 1. In a gas stove, the combination with the burner thereof; of a roof-cap placed above said burner and having such width and surface contour as to shed from the jet orifices of said burner liquids or matter falling from 10 above said burner.
- 15 2. In a gas stove, the combination with the burner thereof; of a ring shaped roof cap set above said burner, leaving an air space between it and said burner, and which projects 15 from the top of said burner out over the burner jets, for the purposes set forth.
- 20 3. In a gas stove, the combination with the burner thereof; of a ring shaped roof cap set above said burner, leaving an air space between it and said burner, and having such 20 width and surface contour as to shed from the jet orifices of said burner liquids or matter falling from above said burner.
- 25 4. In a gas stove, the combination of a ring shaped burner therefor having series of jets directed inwardly and outwardly; and a ring shaped roof cap set above said burner, leaving a communicating passage between it and 25 said burner and between the outer and inner 30 series of jets said roof cap projecting inwardly and outwardly over the burner jets for the purposes set forth.

5. In a gas stove, the combination of a ring shaped burner therefor having inwardly and outwardly directed series of jets; and a ring 35 shaped roof cap set above said burner leaving a communicating passage between it and said burner and between the inner and outer series of jets, said roof cap having such width and contour as to shed from the jet orifices of 40 said burner liquids or matter falling from above said burner.

6. In a gas stove, the combination of a multiple burner having a pivotal movement and each burner of which having a separate feed 45 pipe so arranged that any one of them can be swung in line with a single gas supply by the pivotal movement of said burner; and the gas supply connections.

7. In a gas stove, the combination of a multiple burner that is pivoted to the stove at one side of the burner and each of its burners having a separate feed pipe arranged at the opposite side from the pivot and so placed that any one of them can be swung in line 50 with a single common gas supply by swinging the burner; and the gas connections.

In testimony whereof I affix my signature in presence of two witnesses.

JACOB B. WALLACE.
